DESIGN FOR A TOY

Ladislas Turchanyi, Sashalom, near Budapest,
Hungary, assignor to Magyar Ruggyantaárug-yár Részvénytársaság, Budapest, Hungary, a corporation of Hungary

Application February 21, 1934, Serial No. 50,818

Term of patent 7 years

To all whom it may concern:

Be it known that I, LADISLAS TURCHANYI, a citizen of Hungary, residing in the village of Sashalom, near the city of Budapest, Hungary, have invented a new, original, and ornamental Design for a Toy, of which the following is a specification, reference being had to the accompanying drawing forming a part thereof.

Fig. 1 shows a side perspective of the front of the toy.

Fig. 2 shows a side perspective of the rear of the toy.

I claim:

The ornamental design for a toy substantially as shown.

LADISLAS TURCHANYI.
